Primary Examiner — Joseph Kukella(74) *Attorney, Agent, or Firm* — Scott Griggs; Griggs Bergen LLP(57) **CLAIM**

I claim the ornamental design for an automated railroad signage device, as shown and described.

DESCRIPTION

FIG. 1 is a perspective front view of an automated railroad signage device showing the new design; and

FIG. 2 is a perspective rear view;

FIG. 3 is a bottom view;

FIG. 4 is a front view;

FIG. 5 is a right side view;

FIG. 6 is a left side view;

FIG. 7 is a rear view; and,

FIG. 8 is a top view.

1 Claim, 8 Drawing Sheets(56)
